Primary Examiner — Robert M Spear*Assistant Examiner* — Darcey E Heflin(74) *Attorney, Agent, or Firm* — Greer, Burns & Crain, Ltd.(57) **CLAIM**

The ornamental design for a beverage cup lid, as shown and described.

DESCRIPTION

FIG. 1 is a top perspective view of an embodiment of the present beverage cup lid;

FIG. 2 is a bottom perspective view of same;

FIG. 3 is a top view of the beverage cup lid of FIG. 1;

FIG. 4 is a bottom view of same;

FIG. 5 is a right side view of the beverage cup lid of FIG.

1, both sides being mirror images of each other; and,

FIG. 6 is a side perspective view of the beverage cup lid of FIG. 1 shown on a beverage cup.

The structure shown in broken lines is for environment purposes only and does not form part of the claimed design.
